UNITED STATES PATENT OFFICE.

KARL MÖLLER, OF CHARLOTTENBURG, GERMANY, ASSIGNOR TO GENERAL ELECTRIC COMPANY, A CORPORATION OF NEW YORK.

SIGNAL.

No. 811,238.

Specification of Letters Patent.

Patented Jan. 30, 1906.

Application filed June 12, 1905. Serial No. 264,779.

To all whom it may concern:

Be it known that I, KARL MÖLLER, a subject of the King of Prussia, German Emperor, residing at Charlottenburg, Germany, have 5 invented certain new and useful Improvements in Signals, of which the following is a specification.

My invention relates to signals, and particularly to signals which are operated by solenoids. It is well understood that such signals require much more current for shifting them than is needed for holding them in position when shifted, and it has been proposed heretofore to provide the solenoid with two 10 windings, both used for shifting the signal, and to arrange a switch operated by the signal for cutting out one of the windings when the signal has been shifted to its proper position. Such an arrangement results in a 15 considerable economy of current. A large amount of current is required, however, for shifting the signal, and if the controlling-station is at some distance from the signal conductors of comparatively large size are 20 required to carry the necessary current. This can be avoided by providing a source of current near the signal itself and arranging a relay controlled from a distant point to control 25 the circuit of the solenoid. For the local 30 source of current near the signal it is frequently necessary to employ batteries, and since the solenoid must be maintained continually energized as long as the signal is in clear position the battery is delivering current 35 for the greater part of the time, which is a disadvantage.

My invention consists in connecting only one of the solenoid-windings to the local source of current and connecting the holding-winding, as well as the relay-winding, to the 40 distant control-station. With this arrangement the large amount of current required for shifting the signal is furnished by the local source of current, so that the conductors 45 extending to the distant control-station may be small; but the local circuit is closed only while the signal is being shifted, so that if a battery is used it is working only a very small 50 part of the time and the rate of depreciation is greatly reduced.

My invention accordingly consists in the combination, with a signal, of a solenoid for operating it having two windings, one connected to a local source of current and the

other connected to a distant control-station, 55 together with a relay having its winding connected to the distant control-station and arranged to control the local circuit, and a switch operated by the signal for breaking the local circuit when the signal is in position 60 either directly or by deenergizing the relay.

My invention will best be understood by reference to the accompanying drawing, which shows diagrammatically a signal provided with controlling means arranged in accordance with my invention.

In the drawing, A represents a semaphore-arm provided with the usual counterweight a, arranged to draw the semaphore-arm to danger position, as shown, when the arm is 70 released by the operating means. The means for shifting the signal to clear position consists of a solenoid-core B, provided with two windings, one of which, C C, is connected to a local source of current D, while 75 the other winding c is connected to the distant control-station. E represents a relay, the armature of which, e, is included in circuit with the solenoid-coils C C and the local source of current D. The armature e is provided with a spring e', which holds it in open 80 position, as shown, except when the relay E is energized.

F represents a switch operated by the signal, which when the signal is in danger position, as shown, is held open by the spring f, but which is closed when the signal-arm A is moved to clear position. The closing of switch F short-circuits the winding of relay E.

At the distant control-station is a switch G 90 and a suitable source of current H. The switch G may be operated manually or automatically in any well-known manner.

The operation is as follows: With the signal at "danger" and the several parts in the 95 position shown if the switch G is closed a circuit will be completed from the source of current H through the relay-winding E and solenoid-winding c. The relay-armature e is consequently drawn to closed position, closing the local circuit from the source of current D through the solenoid-winding C C. Both windings of the solenoid are thus energized and cooperate to draw down the core B, 100 so as to shift the signal-arm A to clear position. When this position is reached, switch F is moved to closed position, thereby short-circuiting the relay-winding E. The relay 105

2

releases its armature, thereby opening the local circuit and deenergizing the winding C. The solenoid-winding c is still energized, however, as long as switch G at the distant control-station is kept closed, and consequently the signal-arm is held at clear position. Whenever the switch G at the distant station is opened, the signal-arm is released and returns to danger position, as shown, allowing switch F to open.

It will be understood that for the sake of simplicity I have shown the several parts of the apparatus diagrammatically and that in practice any well-known form of apparatus may be employed. Accordingly I do not desire to limit myself to the particular construction and arrangement of parts here shown, but aim in the appended claims to cover all modifications which are within the scope of my invention.

What I claim as new, and desire to secure by Letters Patent of the United States, is—

1. In combination, a counterweighted signal, a solenoid adapted to shift said signal and having two windings, a local circuit comprising one of said windings and a local source of current, a distant control-circuit including the other winding, a relay connected to said control-circuit and controlling the local circuit, and a switch operated by the movement of the signal and controlling the local circuit.

2. In combination, a counterweighted signal, a solenoid adapted to shift said signal and

having two windings, a local circuit comprising one of said windings and a local source of current, a distant control-circuit including the other winding, a relay connected to said control-circuit and controlling the local circuit, and a switch operated by the movement of the signal and arranged to deenergize said relay to open said local circuit.

3. In combination, a counterweighted signal, a solenoid adapted to shift said signal and having two windings, a local circuit comprising one of said windings and a local source of current, a distant control-circuit including the other winding, a relay connected to said control-circuit and controlling the local circuit, and a switch operated by the movement of the signal and arranged to short-circuit said relay.

4. In combination, a counterweighted signal, a solenoid adapted to shift said signal and having two windings, a local circuit comprising one of said windings and a local source of current, a control-circuit including the other winding and a distant control-station, means controlled from said distant station for closing the local circuit, and means controlled by the movement of said signal for opening the local circuit.

In witness whereof I have hereunto set my hand this 22d day of May, 1905.

KARL MÖLLER.
